UNITED STATES PATENT OFFICE.

HUGO LENTZ, OF HALENSEE, NEAR BERLIN, GERMANY.

MID-EXHAUST STEAM-ENGINE.

1,246,953.

Specification of Letters Patent. Patented Nov. 20, 1917.

Application filed September 23, 1914. Serial No. 863,061.

To all whom it may concern:

Be it known that I, HUGO LENTZ, a citizen of the German Empire, and residing at Halensee, near Berlin, Germany, have invented certain new and useful Improvements in Mid-Exhaust Steam-Engines, of which the following is a specification.

This invention relates to mid-exhaust steam engines of the type comprising exhaust ports controlled by the working piston and a valve in series therewith.

A primary object is to provide an improved exhaust valve such that this controls not only the inlet valves of the cylinder but at the same time an auxiliary exhaust which automatically operates when the compression in the cylinder has attained an inadmissible amount or when a change is made from working with condensation to non-condensation.

Another object of the invention is to arrange the distributing edges of the valve relatively to the edges of the cams provided thereon for the inlet valves in such manner that it is possible to machine the valve in a simple manner and in such a manner that the constrictions in the exhaust port are done away with.

To these ends my invention consists in the construction, arrangement and combination of parts described hereinafter and pointed out in the claims.

One illustrative embodiment of the invention as applied to a compound steam engine which comprises a low-pressure mid-exhaust cylinder is represented by way of example in the accompanying drawings, wherein:

Figure 1 is a cross-section taken on the line 1-1 in Fig. 4,

Fig. 2 shows two vertical sections taken through the engine shown in Fig. 1, the left-hand side being taken on the line 2-2 and on the right-hand on the bent line 2'-2' in Fig. 1,

Fig. 3 is a cross-section taken on the bent line 3-3 in Fig. 4, and

Fig. 4 is a horizontal section taken on the line 4-4 in Fig. 3, the upper part being seen from above and the lower part as seen from below;

Fig. 5 is an enlarged view of the lower part of Fig. 1;

Figs. 6, 7 and 8 are detail sectional views

through the distributing valve taken on the lines 6-6, 7-7 and 8-8, respectively, in Fig. 5, and

Fig. 9 is a cross-sectional view taken on line 9-9 of Fig. 5, looking in the direction of the arrow.

Referring to the drawings, the illustrated compound steam engine of the Woolf type comprises a high-pressure cylinder *o* and a low-pressure cylinder *n* respectively containing the working pistons *a* and *b* (Fig. 4). The two cylinders are connected together at their ends by passage ways *c* and *c'*. Live steam enters at *d'*, passes through the inlet valves *p* and the passage ways *d* into the high-pressure cylinder *o*, flows hence after partially expanding through the passage ways *c* and the intermediate valves *m* into the low-pressure cylinder *n* and after completely expanding through the exhaust ports *e* and the exhaust valve *f* in the exhaust branch *e'*.

The spring-influenced inlet valves *p* are controlled by means of the lay shaft *h* which acts by means of the cam *h'* on the ends of the inlet valve rods *p'*, so that the inlet valves are positively opened and closed in known manner.

The passage of the steam from the high-pressure to the low-pressure cylinder is controlled by the likewise spring-influenced intermediate valves *m* which are driven by cams *i* arranged in known manner immediately at the exhaust valve *f*. These cams *i* coact with the ends of the valve rods *l*.

The escape of the steam from the low-pressure cylinder *n* through the exhaust ports *e* is regulated by the working piston *b* and the rotary valve *f*. The part of this rotary valve which covers the exhaust ports *e* has the section *f'* shown in Fig. 8 and according to its position for the time being closes or opens these ports *e*. The valve *f* is controlled by an eccentric, not shown, whose rod is attached to the rocking lever *g*.

Besides the distributing ports described above additional auxiliary exhaust ports *k* (Fig. 4) are arranged along the low-pressure cylinder *n* which open at one end by way of vertical holes *k'* into the cylinder ends and at the other end into a hole *s'* in the middle support *s* containing the rotary valve *f*, and thus establish a connection between the cylinder ends and the exhaust

- chamber. In the position of the rotary valve f shown in Fig. 5, however, these ports k are constantly closed by the full section t of the valve even when the valve 5 f is rotated. With the parts in their positions shown in Figs. 1 and 5 the condenser is in operation and the low-pressure cylinder works on the pure direct-current or mid-exhaust principle.
- 10 The smaller section u is formed beside the full section t by means of a recess, and the distributing edges 3 of this section u have the position represented in Fig. 7 relatively to the ports k . This auxiliary valve u is intended to act only when, owing to the condensing plant breaking down or to any other reason, the pressure in the low-pressure cylinder exceeds the admissible amount, because then owing to the insertion of this auxiliary valve the ports k are alternately opened and closed and a connection of the cylinder ends with the exhaust is established. The engine then works in part on the counter-current principle.
- 15 In order that the valve u may operate automatically when the condensing plant breaks down, the entire exhaust valve f is mounted displaceably in a casing q , and the one end like a piston closes a space or chamber q' in the casing q , this space or chamber being connected by a tube v with the condenser, so that the pressure of the condenser at any time exists in this space. A spring w in this chamber q' serves for shifting to the right the distributing valve f when the condenser is not operating. When the condensing plant is working the full pressure below atmospheric exists in the chamber q' , so that the entire valve f is then shifted to the left 30 and the solid part of the valve constantly closes the auxiliary exhaust ports k . If the condensing plant breaks down and the pressure in the chamber q' consequently rises the spring w operates, shifts the valve f to the right and renders the part u of the valve operative.
- 35 In order that the rotary valve f may continue to be driven during this displacement its other end has a rectangular projection f'' that is clasped as by a claw by the forked end g' of the driving lever g . By this means the valve member f may be moved to the position shown in Figs. 1 and 5 while continuing to be operated by the lever g . The 40 movement of the valve member to the left (Fig. 5) is limited by the stop 10, while its movement to the right is limited by the inner end g'' of the bearing member for the claw g' . The inner end g'' of this member is arranged slightly eccentric with respect to the adjacent bore for the valve member and the end g'' engages the adjacent portion of the valve member f to limit its movements to the right.
- 45 Referring to Figs. 6 and 8, it will be observed that the cam i for controlling the valve spindles l , l also controls the portion of the long narrow exhaust port at that location, and if in designing this cam i due regard were not given to the width of the 50 exhaust port along the remaining portion of its length, and to the width or angular embrace of the port-closing portion of the valve member f' , the extremities of which are indicated in Fig. 8 by the numerals 4, 4, some 55 special shape would have to be given to the portion of the exhaust port controlled by said cam, in order that no steam would flow out at this point before it would along the rest of the exhaust port. In order to obviate this, I so design the cam i that the width or angular embrace of its upper portion 60 2-2, as shown in Fig. 6, is equal to the width or angular embrace of the upper portion of the cam member f' which controls 65 the remaining length of the exhaust port, so that the width of the top or exhaust port-controlling portion of the valve member f' is uniform throughout its length except at the central portion u - t controlling the auxiliary exhaust port k . By this arrangement the said exhaust port e can be made uniform throughout and the entire valve member f' may be more readily made because it can be simply milled, shallow recesses being necessary only where the cams are located.
- 50 I claim:
1. In a steam engine, the combination of a cylinder having a main exhaust port and an auxiliary exhaust port intermediate said main exhaust port and one end of the cylinder, and adjustable means for opening and closing both of said ports under one adjustment and for opening and closing one of said ports and keeping the other closed under another adjustment.
  2. In a steam engine, the combination of a cylinder having a main exhaust port and an auxiliary exhaust port intermediate said main exhaust port and one end of the cylinder, adjustable means for opening and closing both of said ports under one adjustment and for opening and closing one of said ports and keeping the other closed under another adjustment, and means responsive to the pressure in the exhaust passage of the engine for setting said last named means at its adjusted positions.
  3. In a steam engine, the combination of a cylinder having a mid-exhaust port and other exhaust ports, one intermediate the mid-exhaust port and each end of the cylinder, and valve mechanism for controlling said exhaust ports, said mechanism having means for controlling the mid-exhaust port independently of the other exhaust ports.
  4. In a steam engine, the combination of a cylinder having a mid-exhaust port and auxiliary exhaust ports adjacent the ends of the cylinders, and a rocking valve member for

controlling said exhaust ports, said member having means for opening and closing the mid-exhaust port while holding the auxiliary exhaust ports closed.

5. In a steam engine, the combination of a cylinder having a mid-exhaust port and auxiliary exhaust ports, one intermediate the mid-exhaust port and each end of the cylinder, a valve-controlled member having provision for opening and closing the mid-exhaust port while holding the auxiliary exhaust ports closed, and means operatively related to said valve-control member for rendering it operative to also open and close the auxiliary exhaust ports.

10. In a steam engine, the combination of a cylinder having a mid-exhaust port and auxiliary exhaust ports, one intermediate the mid-exhaust port and each end of the cylinder, a rock shaft having provision for opening and closing the mid-exhaust port and for maintaining the auxiliary exhaust ports closed during normal operation of the engine, and means for shifting said shaft to a position wherein it also opens and closes the auxiliary exhaust ports.

15. In a steam engine, the combination of a cylinder having a mid-exhaust port and auxiliary exhaust ports, one intermediate the mid-exhaust port and each end of the cylinder, a rock-shaft having provision for opening and closing the mid-exhaust port and for maintaining the auxiliary exhaust ports closed during normal operation of the engine, and means operatively related to said shaft and dependent upon the pressure in the exhaust passage of the engine for shifting the shaft upon predetermined increases of said pressure to a position wherein it also opens and closes the auxiliary ports.

20. In a steam engine, the combination of a cylinder having a mid-exhaust port and auxiliary exhaust ports, one intermediate the mid-exhaust port and each end of the cylinder, a valve member, means for rocking the same to control the ports, means responsive to pressure in the exhaust passage of the engine for shifting the valve member in the direction of its length, said member having a valve surface for controlling the opening and closing of said mid-exhaust port, and having a valve surface for closing the auxiliary ports through the rocking arc of the member, and also having a surface for opening and closing said auxiliary ports when the member is shifted responsive to change in said pressure.

25. In a steam engine, the combination of a cylinder having a mid-exhaust port and a main exhaust passage leading therefrom, auxiliary exhaust ports one intermediate the mid-exhaust port and each end of the cylinder, and passages leading from said last named ports to said main exhaust pas-

sage, and means for controlling said main exhaust passage independently of said auxiliary exhaust passages.

30. In a steam engine, the combination of a cylinder having a mid-exhaust port and a main exhaust passage leading therefrom, auxiliary exhaust ports one intermediate the mid-exhaust port and each end of the cylinder, and passages leading from said last named ports to said main exhaust passage, and adjustable means for opening and closing all of said exhaust passages under one adjustment and for opening and closing said main passage and keeping closed said auxiliary passages under another adjust- 80

35. In a steam engine, the combination of a cylinder having mid-exhaust ports and auxiliary exhaust ports, a valve-control shaft mounted for rocking movement and longitudinal shifting, means for rocking said shaft, said means being connected thereto to permit relative longitudinal movement, said shaft having provision for opening and closing the mid-exhaust port and for maintaining the auxiliary ports closed, and means for shifting the shaft to a position wherein it also opens and closes the auxiliary exhaust ports.

40. In a steam engine, the combination of a cylinder having a mid-exhaust port and auxiliary exhaust ports, a valve-control shaft mounted for rocking movement and longitudinal shifting, said shaft having a longitudinally extending arcuate face for controlling the opening and closing of said mid-exhaust port, said face having a width equal to or greater than the width of said mid-exhaust port, said face having arcuate extensions for closing said auxiliary exhaust 100 passages at all times during the rocking movement of said shaft, said face having additional extensions of lesser extent than said last named extensions and adapted to open and close said auxiliary exhaust ports 110 when said shaft is shifted, and means to shift said shaft.

45. In a steam engine, the combination of a cylinder having a mid-exhaust port and auxiliary exhaust ports, a valve-control shaft having circular journal portions, and means for opening and closing said ports when in one position and for opening and closing certain of said ports and keeping closed certain of said ports when in another position, said cylinder having bearings to accommodate said journal portions, a chamber formed around the end of one of said bearings, said chamber communicating with the exhaust passage of the engine, and means to rock said shaft.

50. In a steam engine, the combination of a cylinder having a mid-exhaust port and auxiliary exhaust ports, a valve-control shaft having circular journal portions, and means 125

for opening and closing said ports when in one position and for opening and closing certain of said ports and keeping closed certain of said ports when in another position, said cylinder having bearings to accommodate said journal portions, a chamber formed around the end of one of said bearings, a spring in said chamber and pressing against said shaft, an oscillating member, and means coupling said member and shaft to transmit rotary movement and permit relative longitudinal movement.

15. In a steam engine, the combination of

a cylinder having a mid-exhaust port and other exhaust ports, and a single adjustable valve member for opening and closing all of said ports under one adjustment, and for opening and closing certain of said ports and keeping closed certain of said ports under another adjustment.

20. In testimony whereof, I affix my signature in the presence of two witnesses.

HUGO LENTZ.
